UNITED STATES PATENT OFFICE.

JAMES ARTHUR WILLIAMS, OF ESSEX, CONNECTICUT.

DESIGN FOR A PUZZLE-CASE.

SPECIFICATION forming part of Design No. 27,317, dated July 6, 1897.

Application filed May 11, 1897. Serial No. 636,103. Term of patent 3½ years.

To all whom it may concern:

Be it known that I, JAMES ARTHUR WILLIAMS, a citizen of the United States, residing at Essex, in the county of Middlesex and State 5 of Connecticut, have invented and produced a new and original Design for Puzzle Boxes or Cases, of which the following is a specification, reference being had to the accompanying drawings, forming a part thereof.

10 In the drawings forming part of this specification, Figure 1 is a plan view of my puzzle box or case, and Fig. 2 a central transverse section on the line 2 2, these two views being deemed necessary to fully illustrate my 15 design.

The leading and material feature of my design consists of a circular box or casing composed of a bottom 5 and circular walls 6, the central portion of the bottom being slightly 20 convex or raised, as shown at 7, and provided with a plurality of circular cavities or recesses 8, which are formed therein.

The central circular raised portion of the bottom of the box or casing is partially 25 closed by a circular vertical wall or flange 9, which is open at one side, as shown at 10, and provided with projecting vertical walls 11, and connected with the outer side of the circular central wall 9 are tangential walls

12, which project outwardly into that portion 30 of the box or casing around the central circular wall 9, and extending from the inner end of one of the vertical walls 11 is a radial wall 13, which connects with the circular wall 5, as shown at 14, and connected with the circular side wall 5 are inwardly-directed tangential walls 15, the inner ends of which terminate adjacent to the outer ends of the tangential walls 12, so as to form open spaces 16.

The entire design is symmetrical in form, 40 and the bottom of the box or casing is perfectly smooth and regular throughout with the exception of the central portion thereof, which is slightly raised, as described.

Having fully described my new and original 45 design, I claim as new and desire to secure by Letters Patent—

The design for a puzzle box or case herein shown and described.

In testimony that I claim the foregoing as 50 my invention I have signed my name, in presence of the subscribing witnesses, this 24th day of April, 1897.

JAMES ARTHUR WILLIAMS.
